UNITED STATES PATENT OFFICE.

WILLIAM L. MERSFELDER, OF CINCINNATI, OHIO, ASSIGNOR TO THE STAR FOUNDRY COMPANY, OF COVINGTON, KENTUCKY.

DESIGN FOR A STOVE OR RANGE.

SPECIFICATION forming part of Design No. 31,414, dated August 15, 1899.

Application filed July 24, 1899. Serial No. 725,009. Term of patent 7 years.

To all whom it may concern:

Be it known that I, WILLIAM L. MERSFELDER, a citizen of the United States, and a resident of Cincinnati, in the county of Hamilton and State of Ohio, have invented a certain new and original Design for Ranges or Cooking-Stoves, of which the following is a specification.

My design is intended for ranges or cooking-stoves. Its leading or characteristic feature is the peculiar foliated ornamentation, which is in what is known as the "rococo" style, but in low relief, enlivened by plain bands and shields on the Elizabethan order, as clearly shown in the accompanying drawing.

The accompanying drawing represents a cooking-range embodying my invention.

The top A, its extension-shelf a, and the top shelf B do not differ materially from well-known ranges, excepting that the molding or finishing edge is rounded and the top has an offset at a' extending back of the stove-body C to support the brackets D, which support the upper shelf B and the side brackets or finials E, which rest upon the rear edge of the shelf, and their vertical edges bear against and apparently support the smoke-flue F.

The base of the stove G is enriched by foliated scrolls in the rococo style in low relief and interlaced, as shown in the drawing. The legs H are curved, as shown, and have their

fronts ornamented with shell-and-shield foliage on the Elizabethan order.

The body of the stove is separated from the base by a plain molded band I, the doors of the body being formed in framed panels ornamented like the base; but the oven-door and fire-door have each plain Elizabethan shields j to relieve the surrounding molding, and the handle of the oven-door j² is in shell form, like the top of the legs H. The brackets D are pierced, as are also the finials E, but are ornamented in the same style as the base. The front of the flue F above and below the upper shelf is also ornamented in the same style; but the flue below the shelf has circular plain bands surrounding the foliated ornamentation to throw the ornamentation more fully in relief, and the panels upon each side of the smoke-flue are also ornamented in the same style and inclosed by plain bands for the same purpose. The foliated scroll work, with the dividing plain bands and shells, is the prominent feature of the invention and gives a very pleasing effect to the range.

55
What I claim is—

The design for a stove or range, substantially as shown and described.

WILLIAM L. MERSFELDER.
